FREDERICK W. BROCKSIEPER, OF NEW HAVEN, CONNECTICUT, ASSIGNOR
TO SARGENT AND CO., OF SAME PLACE.

Design No. 4,361, dated September 27, 1870.

DESIGN FOR A BLOWER-HOLDER.

The Schedule referred to in these Letters Patent and making part of the same.

To all whom it may concern:

Be it known that I, FREDERICK BROCKSIEPER, of New Haven, in the county of New Haven and State of Connecticut, have invented a new Design for Blower-Holder; and I do hereby declare that the following, when taken in connection with the accompanying illustration, to be a full, clear, and exact description of the same, and which said illustration constitutes part of this specification, and represents a perspective view.

This invention relates to a design for blower-holder; that is, a device for supporting the blower of fire-grates, when not in use, and consists in the peculiar configuration and ornamentation of the forked ends or sup-

ports, which said ends are connected together by a bar across the base, in the usual manner.

The surface of the holder has a plain raised edge, forming a panel filled with tracery in relief upon a matted surface, as fully represented in the accompanying photographic illustration, to which reference is made.

I claim as my invention—

The design for blower-holder, as shown.

F. W. BROCKSIEPER.
